CARTRIDGE HOLDER

Grover F. Mullins, Westwood, Calif.

Application June 4, 1940, Serial No. 338,800

2 Claims. (Cl. 312—48)

This invention relates to a cartridge holder, and has for the primary object the provision of a device of this character which will accommodate a selected number of cartridges and maintain them for use in a safe and clean condition and substantially free of moisture and dampness and includes a manually operated means for dispensing one cartridge at a time with the utmost safety.

Another object of this invention is the provision of means for supporting the cartridges in a double column with the cartridges of each column lying longways one on the other and the operating means for dispensing the cartridges actuated in such a way that the cartridges will be released first from one column and then the other column until all cartridges have been dispensed from the device.

With these and other objects in view, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation, partly in section, illustrating a cartridge holder constructed in accordance with my invention.

Figure 2 is a transverse sectional view illustrating the device.

Figure 3 is a sectional view taken on the line 3—3 of Figure 2.

Figure 4 is a plan view, partly in section, illustrating a follower plate and a portion of a spring connected thereto.

Figure 5 is a side elevation illustrating one of the springs of the followers.

Figure 6 is a side elevation illustrating a control gate.

Referring in detail to the drawings, the numeral 5 indicates a rigid casing constructed of metal or any other material suitable for the purpose and arranged over said casing is a covering 6 constructed of leather or any other material suitable for the purpose. Located on one of the walls of the casing and carried by the covering is a belt strap 7 to permit the device to be readily mounted on a waist-encircling belt (not shown).

The lower end of the casing is fully open to form a discharge end or mouth to the casing designated by the character 8 and one of the walls of the casing is extended below the other

walls and curved to form a lip 9 to coact with a controlling gate 10 for the release of cartridges from the casing.

The casing has mounted therein a partition 5 dividing the casing into compartments 12 and 13. The cartridges are arranged in the compartments in superimposed relation lying endwise, as clearly shown in Figures 2 and 3 of the drawings. The cartridges thus arranged in the compartments form a double column of cartridges held in the compartments by the controlling gate 10. The cartridges are urged in the direction of the mouth 8 by spring influenced followers 15 slidably mounted in the compartments and each consisting of an elongated plate 16 bearing on the uppermost cartridge and on which are formed lips or tongues 17 for securing thereon an expansion spring 18 of the type shown in Figure 5. The springs also bear against the top wall of the casing.

Finger pieces 18 are pivotally secured to the follower plates 16 and extend through slots 19 formed in opposite walls of the casing 5 and covering 6. The upper ends of the slots are provided with offset branches 19' in which the finger pieces may be moved for holding the springs compressed and the follower plates in the upper ends of the compartments so that the cartridges may be readily placed in the compartments.

Opposite walls of the casing 5 are provided with entrances 20 normally closed by slideable doors 21 for the purpose of permitting when the doors are open the cartridges to be placed into the compartments. The doors are slidably mounted on the casing by pins 22 carried by said casing and extending through slots 23 in the doors. The heads of the pins have a frictional fit with the doors so as to retain the doors either in their open or closed positions.

After the cartridges have been arranged in the compartments, as shown in Figure 2, the finger pieces 18 are moved out of the branches 19' of the slots 19 so that the followers are free to act on the cartridges for urging them in the direction of the mouth 8.

The gate 10 consists of a substantially flat elongated member 24 provided with pintles 25 on the ends thereof which are journaled in opposite walls 50 of the casing 5 adjacent to the mouth 8. A substantially L-shaped arm 26 is formed on one end of the member 24 adjacent one of the side edges and carries at its free end a rounded portion 27 received within a forked end 28 of a substantially L-shaped operating lever 29 pivotally mounted on

the casing, as shown at 30. A finger grip 31 is connected to the operating lever 29.

A coil spring 32 has one end connected to the arm 26 and the other end connected to the pivot 30. The purpose of the spring 32 is to maintain the gate to either side of a dead center position. The opposite faces of the member 24 have formed therein grooves 33 in which the cartridges may rest. Also it is preferable that the member 24 have openings 34 formed therein which extend the full length thereof for the purpose of reducing the weight of the member 24.

The member 24 of the gate acts to control the movement of the cartridges one at a time from the compartments and in an alternate manner from said compartments. To remove cartridges one at a time and alternatingly from the compartments, the lever 29 is moved first in one direction on its pivot to rotate the member 24 in one direction which releases the lowermost cartridge from one of the compartments and the lever is then moved in a reverse direction to rotate the member 24 in a reverse direction to release the lowermost cartridge from the other compartment. The described movements of the lever 29 are repeated until all cartridges are dispensed from the casing.

By referring to Figure 2 it will be seen that when the lever 29 is moved downwardly the member 24 of the gate 10 is caused to rotate in a clockwise direction with a portion thereof moving away from the lip 19 and coming to rest against one of the shorter walls of the casing. This movement frees the lowermost cartridge in the compartment 12. An upward movement of the lever 29 in Figure 2 brings the member 24 of the gate 10 back into the position as shown in Figure 2 and as the gate moves into this latter-named position a cartridge is freed from the compartment 13.

Thus it will be seen that through the pivotal movement of the lever 29 in an upward and downward direction with respect to the casing the cartridges will be rapidly dispensed first from one compartment and then the other compartment of the casing with complete safety. The removal of the cartridges can be brought about extremely

rapidly depending entirely on how fast the lever 29 is actuated.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a device of the class described, a rigid casing having a mouth, a partition in said casing to form compartments to receive cartridges, spring pressed followers in said compartments for urging the cartridges toward the mouth, a gate for controlling the cartridges through said mouth one at a time and alternatingly from one compartment and then from the other compartment, an operating means for said gate, said casing having openings communicating with the compartments to permit cartridges to be placed therein, doors for opening and closing said openings, said casing having slots communicating with the compartments, and provided with lateral branches, and finger pieces pivoted on the followers and operating in the slots and adapted to be moved into the branches for holding the followers at one end of the compartments to permit filling of said compartments with the cartridges by way of the openings.

2. In a device of the class described, a casing containing cartridges and having a mouth, a spring influenced follower acting on the cartridges to urge them in the direction of the mouth, a gate member having two positions pivotally mounted in the mouth of the casing for rotation into either of its positions, an arm secured on the gate member and having a rounded end, a substantially L-shaped operating lever pivoted on said casing and provided with a finger ring and having a forked end to receive the rounded end of said arm, and a coil spring connected to the pivot of said operating lever and to said arm for retaining the gate member in either of its positions.

GROVER F. MULLINS.
